UNITED STATES PATENT OFFICE.

JAMES SOLOMON MCKENZIE, OF MIAMI, FLORIDA.

DUST-GUARD FOR RAILWAY-CARS.

SPECIFICATION forming part of Letters Patent No. 634,473, dated October 10, 1899.

Application filed March 17, 1898. Serial No. 674,207. (No model.)

To all whom it may concern:

Be it known that I, JAMES SOLOMON MCKENZIE, a citizen of the United States, residing at Miami, in the county of Dade and State of Florida, have invented certain new and useful Improvements in Dust-Guards for Railway-Cars; and I do declare the following to be a full, clear, and exact description of the invention, such as will enable others skilled in the art to which it appertains to make and use the same.

The invention relates to an improvement in dust and cinder guards for the windows of railway-cars.

15 The object of the invention is to provide a simple and inexpensive device of this character which may be easily attached to the windows of cars now in general use and which will effectively catch the dust and cinders 20 which work their way between the lower rail of the sash and the window-sill.

With this object in view the invention consists in certain features of construction and combination of parts, which will be hereinafter fully described and claimed.

In the drawings, Figure 1 is a perspective view taken from the outside of the car, showing my improved dust and cinder guard in position. Fig. 2 is a similar view taken from 30 the inside of the car. Fig. 3 is a transverse section of the dust and cinder guard.

In the drawings, 1 denotes the window-sill; 2, the side frames; 3, the window-sash, and 4 the blind.

35 5 denotes the dust and cinder pan, which is approximately semicylindrical in cross-section and snugly fits the inside faces of the side frames 2.

7 denotes a slide on the inner beaded face 40 of the pan to permit of access to the thumb-button 8 on the lower rail of the blind, and 9 denotes a similar slide to permit the sash-lock to be reached and manipulated.

10 denotes a longitudinal brush-shaft loosely 45 journaled in bearing-brackets 11, fixed in the end walls 66. A flexible cord 12 is wound around the shaft in one direction, and a similar cord 13 is wound around the shaft in a reverse direction, both cords passing through 50 suitable orifices in the pan and provided with grip-knobs 15, so that by alternately drawing said cords inwardly the shaft will be rotated

in opposite directions. This shaft is provided with a circular brush 16, the diameter of which is greater than the space between 55 the lower sash-rail 3 and the inside face of the pan, whereby when in position the fibers or tufts of the brush press against the lower sash-rail 3 and its pane of glass as well as the inner face of the pan. It is evident, therefore, that should any dust or cinders work between the lower edge of the rail 3 and the sill and thence upwardly they would be caught by the brush and be prevented from escaping into the car. 65

17 denotes a removable diaphragm or false bottom supported by the cross-braces 18, 18, the projecting edges of which rest against the curved parallel sides of the pan in such a manner as to leave passage-ways or openings 70 19 between the false bottom 17 and the sides of the pan, as shown in Fig. 1, so that the dust and cinders arrested by said brush may be dislodged therefrom and drop into the bottom of the pan by rotating the brush by 75 the operating-cords 12, 13.

The operation of the device is very simple and will be readily understood from the preceding description taken in connection with the accompanying drawings, from which it 80 will be seen that particles of coal-dust and cinders which may enter under the window-sash will be caught by the brush and be dislodged therefrom by its rotation and fall through the passage-ways 19 into the bottom 85 of the pan.

The pan may be provided with an opening 20 in its end, through which the accumulated dust and cinders may be dumped by removing the pan from its position and tilting the 90 end with the opening downward.

Having thus described the invention, what is claimed, and desired to be secured by Letters Patent, is—

1. A dust and cinder guard for railway-cars 95 comprising a semicylindrical pan provided with a diaphragm the width of which is less than that of the pan, whereby passages are formed between its edge and the sides of the diaphragm, and a rotary brush the diameter 100 of which is greater than the width of the diaphragm, whereby, when in position, the brush will be pressed against the lower rail of the window-sash in position to catch any

dust and cinders which may enter the car under said rail, substantially as and for the purpose set forth.

2. A dust and cinder guard for railway-car windows comprising the semicylindrical pan provided with slides 7 and 9, and the removable diaphragm 17, horizontally arranged in said pan so as to form passage-ways 19 between the parallel edges of said diaphragm and the sides of the pan; in combination with a rotary brush adapted to press against the

inner side of the lower sash and catch any cinders or dust which may work up under the lower edge of the same, substantially as and for the purpose set forth.

In testimony whereof I have hereunto set my hand in presence of two subscribing witnesses.

JAMES SOLOMON MCKENZIE.
